[57] CLAIM

The ornamental design for an infant cuddle mattress, as shown and described.

DESCRIPTION

FIG. 1 is a perspective view of the infant cuddle mattress; FIG. 2 is a perspective view of the infant cuddle mattress showing the opposite face and opposite end to that of FIG. 1.

FIG. 3 is a plan view showing one face of the infant cuddle mattress, with the opposite face being the same in mirror image;

FIG. 4 is a side elevation view of the infant cuddle mattress; FIG. 5 is a side elevation view of the infant cuddle mattress, taken from the side opposite to that of FIG. 4;

FIG. 6 is an end elevation view of the infant cuddle mattress; and,

FIG. 7 is an end elevation view of the infant cuddle mattress, taken from the end opposite to that of FIG. 5.

A description of the appearance of the article is as follows: an infant cuddle mattress as illustrated in the attached drawing Figures.

1 Claim, 2 Drawing Sheets

FIG. 1.FIG. 2.FIG. 3.FIG. 4.FIG. 5.FIG. 6.FIG. 7.
